D. McCurdy,

Truss Bridge.

No. 104,867.

Patented June 28, 1870.

Fig. 1.

United States Patent Office.

DAVID McCURDY, OF OTTAWA, OHIO.

Letters Patent No. 104,867, dated June 28, 1870; antedated June 17, 1870.

IMPROVEMENT IN BRIDGES.

The Schedule referred to in these Letters Patent and making part of the same.

To all whom it may concern:

Be it known that I, DAVID McCURDY, of Ottawa, in the county of Putnam and in the State of Ohio, have invented certain new and useful Improvements in Bridges; and do hereby declare that the following is a full, clear, and exact description thereof, reference being had to the accompanying drawing and to the letters of reference marked thereon making a part of this specification.

The nature of my invention consists in the construction and general arrangement of a "bridge," as will be hereinafter fully set forth.

In order to enable others skilled in the art to which my invention appertains to make and use the same, I will now proceed to describe its construction and operation, referring to the annexed drawing, in which—

Figure 1 is a side view, and

Figure 2, a bottom view of my bridge.

A represents the arch or girder of my bridge, formed of plank trussed within itself by bolts *a a*, passing in the direction of the center of the circle, and by vertical rods *B B*.

The rods *B B* are, at their lower ends, provided with clamps *b*, through which the cords *e* pass, said clamps being tightened by means of nuts *d d*, above and below the clamp on the rod *B*, said rods being secured on top of the arch *A* by means of nuts *e*, and each alternate rod is further secured by jam-nuts *f* under the arch.

The jam-nuts *f f* may be used on every rod, if deemed necessary to fully secure the arch; but, in that case, each alternate rod is to be a very little shorter, so that, when the tension of the cords is brought up, all the spring or vibration, and contraction and expansion, will be taken up.

The arch is tied overhead by means of cross-braces, *D D*, and may be tied at the chords below in the same

manner, as well as by each joist; and to prevent the arch from twisting, a block, *E*, of metal or wood, is put in at each end under the arch, said block being bolted with the timber *G* below, through the arch which makes the stops at the abutment, with the shoe *H* resting on a metal plate or plank, *I*, free and independent of the abutment endwise, but secured sideways.

The chords *C* pass through the shoes *H*, and are secure and tightened by nuts *i i*.

The joists *J J* are placed around the vertical rods *B B*, and rest upon the chords *C C*, or rather upon the clamps *b b*, through which said chords pass. The floor is laid upon the joists, with suitable railing if the arch is very high, but if not so high, then the arch and rods make the railing.

Having thus fully described my invention,

What I claim as new, and desire to secure by Letters Patent, is—

1. The arrangement of the arch *A*, rods *B B*, chords *C*, bolts *a a*, clamps *b b*, nuts *d d* and *e*, and jam-nuts *f*, all substantially as shown and described.

2. The block *E* and timber *G*, bolted to the arch *A*, substantially as and for the purposes herein set forth.

3. A bridge, when its parts are constructed, arranged, and combined substantially as herein shown and described.

4. The combination in a bridge of the two parallel chords *C C*, notched clamps *b b*, nuts *d d*, and vertical tie-rods *B B*, all substantially as set forth.

In testimony that I claim the foregoing, I have hereunto set my hand this 1st day of November, 1869.

DAVID McCURDY.
